UNITED STATES PATENT OFFICE.

RAWDON EVANS RAMBO, OF WILKINSBURG, PENNSYLVANIA, ASSIGNOR TO WESTINGHOUSE ELECTRIC & MANUFACTURING COMPANY, A CORPORATION OF PENNSYLVANIA.

PNEUMATIC BRUSH HOLDER.

Application filed April 8, 1924. Serial No. 704,987.

To all whom it may concern:

Be it known that I, RAWDON EVANS RAMBO, a citizen of the United States, and a resident of Wilkinsburg, in the county of Allegheny and State of Pennsylvania, have invented a new and useful Improvement in Pneumatic Brush Holders, of which the following is a specification.

My invention relates to brush holders for dynamo-electric machines and it has special reference to brush holders of the type in which the brush is held in contact with the commutator cylinder by pneumatic pressure.

15 In devices of this type in the prior art, certain inherent defects have been found which are overcome by my invention. It has heretofore been usual in pneumatic brush holders to apply the pressure to the brush by means of a plunger engaging the brush and operated by pneumatic pressure applied to it.

Brush holders of the type just mentioned have been found unsatisfactory, because 25 they do not maintain the brush in constant, even contact with the commutator cylinder during the operation of the machine. Irregularities in surface of the commutator cylinder resulted in causing the brush to 30 vibrate or chatter, as the commutator rotated, and the inertia of the piston increased the time taken by the brush to return to the commutator surface after passing over a rough spot thereon. As a consequence, 35 cracking and splintering of the brush frequently resulted and the commutation was not as good as it should be.

One of the objects of my invention is to provide a brush holder wherein the brush 40 may be firmly held against the commutator cylinder by the direct application of pneumatic pressure to the brush.

Another object is to provide a brush holder of the above-mentioned character 45 which will not require the connection of leads to the brush proper.

Another object is to provide a brush holder in which the application of pressure to the brush will be such that, although 50 the brush will be maintained in good contact with the commutator cylinder and will be automatically adjusted to the irregularities of the surface thereof, it will not be

splintered or cracked or otherwise damaged by the maintenance of the proper degree of 55 pressure.

Another object is to provide a brush holder of the pneumatic type in which the brush may be readily installed or removed, and to which it may be closely connected 60 and finely adjusted.

Another object is to provide a brush holder which shall be of few parts of simple and cheap construction, shall have a high degree of efficiency, and shall be capable of maintaining a positive, but elastic, 65 pressure upon the brush without damage thereto, and which may have other advantages and results more specifically herein- 70 after set forth.

My invention consists in the particular organization, combination, and arrangement of parts hereinafter described and more specifically set out in the appended claims.

In the accompanying drawing, in which 75 like numerals of reference indicate corresponding parts,

Figure 1 is a view in side elevation of an assembly of four of my improved brush holders, operably related to a commutator 80 cylinder, only a fragmentary portion of which is shown.

Fig. 2 is a vertical cross-sectional view taken on the line II—II of Fig. 1, showing my improved brush holder mounted on 85 a portion of a supporting yoke, and

Fig. 3 is a vertical cross-sectional view of a modified form of my improved brush holder, showing a brush holding chamber 90 of uniform size.

In Fig. 1 is shown a sectional view of a commutator cylinder 1, in operative relation to which an assembly of pneumatic brush holders 2 is mounted. In the device as shown in Fig. 1, there are assembled 4 95 brush holders. Each brush holder is carried upon a supporting arm or yoke 3, which is provided with an enlarged end 4 having an inset or incut portion 5 and an opening 6 therein, the latter being adapted to receive 100 a stud bolt 7 which engages a threaded aperture 8 in a lug or foot portion 9 of the brush holder body portion 10.

The brush holder box or body may be 105 of any desired outward formation, but must be provided with an interior chamber 11 of

such size and shape as to operably receive and retain the brush 11a, which may be of any usual or desired size and shape.

In the form of brush holder shown in Fig.

- 5 2, one side of the brush holder box, or more especially the chamber 11 therein, is of uniform shape, in this instance a straight surface, while the upper portion of the opposite side is provided with an incut channel or enlarged portion 12. This channel or enlarged portion 12 extends from the top of the brush holder box to approximately its middle point and is provided in order to permit convenient removal of the brush 11 from the brush holder box, when because of breakage or other reason, such removal is desired. The brush 11 is provided, near its upper end, adjacent to the enlargement or slot 12, with a notched or incut portion 13 which is so arranged as to receive a hook or other implement that can conveniently be inserted into the brush holder box, along the channel 12 and into the notch 13, in order to effect the convenient removal of the brush.
- 15 25 The lower portion of the front face of the brush holder chamber is provided with a series of laterally disposed substantially parallel channel portions 14, spaced apart from each other, which act as a series of baffles to control the flow of air in that portion of the chamber when the brush holder is under the intended operating pressure. There is also, in the lower portion of the rear face of the brush holder chamber, a substantially vertically disposed channel portion 15, at the ends of which there are provided outlets or vents 16 and 17, respectively, which communicate with the atmosphere.
- 30 40 45 50 The brush holder box or body is provided at its top with laterally extending lugs or flanges 18 and 19 provided with threaded openings 20 and 21. Seated upon the top flanged end of the brush holder box is a cap or cover 22 which is also provided with flanges or lugs 23 and 24 similar to the lugs 20 and 21 of the main body portion of the brush holder box. The lug or flange portions 23 and 24 of the cap or cover 22 are provided with openings 25 and 26 which register with the openings 20 and 21 in the flanged portion of the brush holder box.
- 55 60 65 The cap 22 is held in operative relation to the brush holder box, closing the upper end thereof, and making an air-tight joint therewith, by means of stud bolts 27 and 28, threaded into the openings 20 and 21 in the brush holder box and passing through the openings 25 and 26 in the cap 22. It will be understood that although I show means of holding the cap in operative position on the brush holder box, any other suitable fastening means may be employed.
- 69 75 85 The cap 22 is provided with a substantially centrally positioned tubular portion 29 having an inlet or opening 30 which ex-

tends through the cap 22 and communicates with an opening 31 in the base of the top or cover 22, so that pneumatic pressure may be applied to the chamber 11 and to the brush 11a therein, when the opening 30 is connected to one or more pipes 32, supplying pressure from a source not here shown.

I assemble my brush holder by mounting it upon the supporting yoke 3, inserting the brush 11a therein, properly closing the top by the cap 22, and connecting the brush holder chamber with a source of pneumatic pressure through the pipes 32. The operation of the device is as follows.

Pressure, approximately three pounds to the square inch, is admitted to the chamber 11, and the brush, receiving this pressure upon its forward face, is forced into close and tight contact with the rear face of the brush holder chamber. When this takes place, such air as may be between the brush and the rear face of the brush holder chamber, is forced into the channel 15 and out to the atmosphere through the vents 16 and 17. I thereby utilize the pneumatic pressure to form a good contact between the brush and the brush holder box, and by this means I am enabled to eliminate the use of leads connected to the brush.

Having adjusted the brush to the commutator cylinder, the desired pneumatic pressure is applied to the brush head and the brush is thus held in firm, close but elastic contact with the commutator cylinder so that as the cylinder rotates it will automatically adjust itself to irregularities of the commutator surface. The air cushion formed in the upper end of the brush holder chamber permits a resilient action of the brush upon the commutator cylinder so that it will maintain a perfect contact while at the same time it will not be subject to the chattering, cracking, splintering or other disintegrations which are encountered in pneumatic brush holders of the type applying pressure to the brush by means of a plunger. Not only is this true, but I am enabled to maintain a perfect contact by my device with the use of pressure of approximately three pounds per square inch above atmospheric pressure whereas in the plunger type of pneumatic brush holders where the pressure is applied to the brush end by a plunger of comparatively small cross-sectional area, the pressure of this plunger against the brush frequently exceeds 25 or 30 pounds per square inch and results in defective operation.

When the brush wears and moves downwardly under pressure, the baffles or channels 14 operate to trap air which may pass between the front face of the brush and the face of the front portion of the brush holder chamber and prevent or curtail the leakage of the air from the brush holder chamber,

while at the same time exerting a pressure tending to hold the brush firmly in contact with the rear face of the brush holder chamber in order to conduct the collected current from the brush.

When the brush has worn to such length that the top end is below the vent 17, the whistling or noise produced by the exhausting air through this vent serves as a signal indicating the need for renewal of the brush. This may be accomplished, as before stated, by the removal of the cap 22 and the lifting out of the brush by means of a hook or other implement which can be made to engage the slot 13 in the upper end of the brush. A new brush may be placed in the holder and the cap replaced.

In Fig. 3 a brush 11a operates in a chamber 33 in substantially the same manner as that explained in connection with the type shown in Fig. 2, except that there is no enlargement of the upper portion of one side of the brush holder chamber. In some respects this is my preferred form of construction, and I believe a better contact may sometimes be obtained between the brush and the brush holder in this type of chamber and a greater efficiency of the brush thereby secured.

I prefer to construct my brush holder box of brass, although any suitable metal or material may be used which will provide a good collector of current from the brush and a sliding relation between the brush and the brush holder box with the minimum amount of friction.

It will be seen, therefore, that my improved brush holder is of extremely simple construction, of few parts and of a high degree of efficiency; it effects the collection and distribution of the current without leads connected to the brush; it automatically provides a signal when there is need of renewal of the brush; it results in the elimination of the defects heretofore known in pneumatic brush holders and prevents the chattering, shattering, splintering and other disintegration of the brushes; it results in long life and efficiency of the brush itself, and it has other advantages not specifically herein set forth.

Although I have shown but two embodiments of my invention, yet I do not wish to be limited thereby except as the state of the art and the appended claims may require, for it is obvious that certain modifications,

reorganizations and combinations of parts may be made without departing from the spirit and scope of my invention.

I claim as my invention:

1. A current-collecting device comprising a brush holder having a brush-holding pressure chamber, means for applying fluid pressure to the head of said chamber, and a brush slidably fitting in said chamber and operating as a piston actuated by said fluid pressure, said device comprising transversely extending fluid pockets between said brush and the side wall of said chamber for limiting the escape of fluid. 60

2. A current-collecting device comprising a brush holder having a brush-holding pressure chamber, means for applying fluid pressure to the head of said chamber, a brush slidably fitting in said chamber and operating as a piston actuated by said fluid pressure, and means for causing the fluid pressure to be greater on one side face of the brush than the other for holding said brush in firm contact with one side wall of the 70 chamber. 75

3. A current-collecting device comprising a brush holder having a brush-holding pressure chamber, means for applying fluid pressure to the head of said chamber, a brush slidably fitting in said chamber and operating as a piston actuated by said fluid pressure, said brush holder having transversely extending fluid pockets between said brush and one side wall of said chamber, and 80 means for preventing the accumulation of fluid between said brush and the opposite side wall of the chamber. 85

4. A current-collecting device comprising a brush holder having a brush-holding pressure chamber, means for applying fluid pressure to the head of said chamber, and a brush slidably fitting in said chamber and operating as a piston actuated by said fluid pressure, said device being provided with 90 fluid-escape channels between said brush and one side wall of the chamber. 95

5. The combination with a brush holder, of a brush mounted therein, said brush having a notch near the top of a side face thereof, and said holder having an enlarged channel adjacent said notch for facilitating the removal of the brush. 105

In testimony whereof, I have hereunto subscribed my name this 28th day of March 1924. 110

RAWDON EVANS RAMBO.
